SIGNORS TO FRIGIDAIRE CORPORATION, OF DAYTON, OHIO, A CORPORATION OF
DELAWARE

REFRIGERATING APPARATUS

Application filed March 31, 1928. Serial No. 266,399.

This invention relates to refrigerating apparatus and particularly to refrigerating apparatus operated by motor vehicles.

One of the objects of the invention is to provide a refrigerated motor vehicle with convenient and economical means for supplying refrigeration at all times.

More specifically it is an object of the invention to provide a refrigerating apparatus for refrigerating a motor vehicle which is driven from the vehicle motor and is provided with improved means for controlling the operation of the refrigerating system.

Another object of the invention is to provide a refrigerating system on a motor vehicle with means for insuring operation of the vehicle motor whenever there is refrigerating demand.

Further objects and advantages of the present invention will be apparent from the following description, reference being had to the accompanying drawing, wherein a preferred form of the present invention is clearly shown.

The single figure of the drawing indicates diagrammatically a refrigerating system in connection with a motor vehicle constructed in accordance with our invention.

Referring to the drawing 10 designates any suitable motor vehicle operated by a motor 11 which includes the usual fan 12, radiator 13 and accessory shaft 14, and is provided with the usual starting motor 15. The starting motor is provided with the usual manually operated switch 16 which closes the circuit 17 from the battery 18 through the starting motor to ground. The motor is also provided with the usual ignition circuit diagrammatically represented as including a circuit-breaker 20, low tension coil 21, and ignition switch 22, all connected in series between the battery main 18' and ground, together with a high tension coil 23, distributor 24 and spark plugs 25.

The vehicle carries a refrigerating system diagrammatically represented as including a compressor 30 mounted on the motor frame, a condenser 31 which may be mounted adjacent the radiator and in front of the fan 12 to be cooled by the latter, and an evaporator 32 dis-

posed within an insulated compartment on the vehicle and diagrammatically represented by 34. The particular construction of the apparatus so far described is immaterial to the present invention and may be of any desired form.

The compressor 30 is mounted so that its driving shaft 36 is in alignment with the accessory shaft 14 and may be coupled to the latter by means of a clutch 37 herein represented as of the magnetic type. The compressor crankcase may contain any desired gearing (not shown) for effecting the desired speed ratio between the vehicle motor and compressor. Preferably any suitable form of overrunning or slipping clutch is provided for insuring a substantially constant compressor speed in spite of variation in the speed of the vehicle motor. As is known such clutches permit slipping or disconnection between the driving and driven members whenever the speed of the driven member is above a predetermined value. Consequently at any speed of the vehicle motor above a predetermined low speed the compressor will be driven at a constant speed. The particular form of such clutch is immaterial to the invention but an example of one suitable form of construction is shown in the patent to Apple No. 698,888, April 29, 1902. A thermostat is provided for actuating the compressor in response to the demand of the evaporator and includes a bulb 39 disposed at any suitable point within the refrigerated compartment 34, charged with a volatile liquid and connected by means of conduit 39a to a metal bellows 40. The metal bellows thus contracts and expands in response to the temperature existing within the compartment 34 and actuates a snap switch 42 by means of the lever 43. The switch is provided with an insulating rod 45 carrying three contact blades, 46, 47 and 48, all of which are elevated to the position shown in the drawings when the bellows collapses in response to low temperature within the compartment 34 and which are lowered to close their respective circuits whenever the bellows expands in response to a high temperature. The contact blade 46,

shown in the drawings when the bellows collapses in response to low temperature within the compartment 34 and which are lowered to close their respective circuits whenever the bellows expands in response to a high temperature. The contact blade 46,

when closed, completes the ignition circuit from the low tension coil 21 to ground in parallel with the ignition switch 22. The contact blade 47, when closed, connects the battery main 18' to the wire 50 which is connected to the governor switch 51, to be described below, and which may connect the wire 50 to the wire 52 thus completing the circuit to the cranking motor 15. The contact blade 48, when closed connects the battery main 18' to the wire 53 which also leads to the governor switch 51, and which may be connected by the governor switch through the wire 54 to the magnetic clutch 37, the other terminal of which is grounded. The accessory shaft 14 is provided with any suitable governor 55 which operates the switch 51 which completes the connection between the wires 50 and 52 when the motor is idle, but breaks the connection between these wires whenever the motor is running.

The system operates as follows: Whenever it is desired to operate the vehicle motor the ignition switch 22 is closed and the manually operated switch 16 is closed to operate the starting motor 15 until the vehicle motor becomes self operative, in the usual manner. When the temperature within the compartment 34 rises to the point where refrigeration is required, the switch 42 is closed, and whenever the temperature is lowered to the point where refrigeration is not required this switch is opened. Assuming that the vehicle motor is not operating when the switch 42 is closed, the governor switch is in the position indicated in full lines, completing contact between the wires 50 and 52. The contact 46 completes the ignition circuit. The contact 47 completes the circuit to the cranking motor which thereupon cranks the vehicle motor until the latter becomes self-operative. When this occurs the governor switch moves from the full line to the dotted line position, breaking contact between wires 50 and 52, and thus interrupting the cranking motor circuit and establishing contact between wires 53 and 54, thus completing the circuit to the magnetic clutch 37 since the contact 48 has in the meantime been closed. The compressor is now operated from the vehicle motor until the refrigeration demand has been satisfied, at which time the switch 42 will be opened, breaking the ignition circuit and stopping the vehicle motor, unless in the meantime the switch 22 has been closed by hand to prevent stopping of the motor when refrigeration demand ceases.

If the vehicle motor should be running when the automatic switch 42 closes the governor switch 51 will be in the dotted line position as above described, and the contact 48 will thereupon immediately energize the magnetic clutch to operate the compressor. The cranking motor 15 cannot be actuated because

its circuit has been interrupted by the governor switch.

It will thus be appreciated that the above described system provides means for insuring operation of the compressor from the vehicle motor at all times, whether the vehicle be in operation or idle, and that the operation of the refrigerating system is entirely automatic in response to refrigeration demand.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising in combination, a motor vehicle, a motor for driving the vehicle, a refrigerating system including a compressor, and means for mechanically connecting the compressor to the vehicle motor in response to refrigerating demand.

2. Refrigerating apparatus comprising in combination, a motor vehicle, a motor for driving the vehicle, a refrigerating system including a compressor adapted to be operated by the vehicle motor, and means for automatically starting the vehicle motor in response to refrigerating demand.

3. Refrigerating apparatus comprising in combination, a motor vehicle, a refrigerating system including a compressor adapted to be operated by the vehicle motor, manually operated means for starting the vehicle motor, means for automatically starting the vehicle motor in response to refrigeration demand, and means responsive to running of the vehicle motor for preventing operation of the automatic starting means.

4. Refrigerating apparatus comprising in combination, a motor vehicle, a motor for driving the vehicle, a refrigerating system including a compressor adapted to be operated by the vehicle motor, means for starting the vehicle motor in response to refrigeration demand, and means for stopping the vehicle motor in response to cessation of demand.

5. Refrigerating apparatus comprising in combination, a motor vehicle, a refrigerating system including a compressor adapted to be operated by the vehicle motor, means for starting the vehicle motor in response to refrigeration demand, and means operating automatically in response to cessation of refrigerating demand and tending to stop the vehicle motor, and manually operated means for preventing the motor from stopping in response to cessation of refrigerating demand.

6. Refrigerating apparatus comprising in combination, a motor vehicle, a motor for driving the vehicle, a refrigerating system carried by the vehicle, a control circuit for the vehicle motor, manually operated means for completing the circuit, and means oper-

ated by the refrigerating system in response to refrigerating demand for completing the circuit.

7. Refrigerating apparatus including a motor vehicle having an ignition circuit, a refrigerating system carried by the vehicle, manually operated means for completing or interrupting the ignition circuit, and means operated automatically by the refrigerating system in parallel with the manual means for completing or interrupting the ignition circuit.

8. Refrigerating apparatus including a motor vehicle, a cranking motor for the vehicle motor, a refrigerating system carried by the vehicle, a circuit for the cranking motor, manually operated means for completing or interrupting the circuit, and means operated automatically by the refrigerating system in parallel with the said manual means for completing or interrupting the circuit.

9. Refrigerating apparatus including a motor vehicle, a cranking motor for the vehicle motor, a refrigerating system carried by the vehicle, parallel circuits for the cranking motor, manually operated means for completing or interrupting one of the circuits, means operated automatically by the refrigerating system for completing or interrupting the other circuit, and means for interrupting the last mentioned circuit in response to running of the vehicle motor.

10. Refrigerating apparatus comprising in combination a motor vehicle, a refrigerating system including a compressor, means for connecting the compressor to the vehicle motor in response to refrigerating demand, and means for preventing the operation of the connection means when the vehicle motor is not operating.

11. Refrigerating apparatus comprising in combination a motor vehicle, a motor for driving the vehicle, a refrigerating system including a compressor, means for connecting the compressor to the vehicle motor, a control circuit for said connecting means and means responsive to operation of the motor for closing or interrupting said circuit.

12. Refrigerating apparatus comprising in combination a motor vehicle, a motor for driving the vehicle, a refrigerating system including a compressor, means for starting the vehicle motor in response to the condition of the refrigerating system and means responsive to running of the motor for connecting the compressor to the vehicle motor.

13. Refrigerating apparatus comprising in combination a motor vehicle, a motor for driving the vehicle, a refrigerating system including a compressor, means for connecting the compressor to the motor in response to refrigerating demand, and means for stopping the motor and disconnecting the compressor in response to cessation of demand.

14. Refrigerating apparatus comprising

in combination a motor vehicle, a motor for driving the vehicle, a refrigerating system including a compressor, manually operated means for starting and stopping the motor, means responsive to refrigerating demand for connecting the compressor to the motor and for preventing the manually operated means from stopping the motor.

15. Refrigerating apparatus comprising in combination a motor vehicle, a motor for driving the vehicle, a refrigerating system including a compressor, a clutch for connecting the compressor to the vehicle motor, and means actuating the clutch in response to refrigerating demand.

16. Refrigerating apparatus comprising in combination a motor vehicle, a variable speed motor for driving the vehicle, a refrigerating system including a compressor, and means for mechanically driving the compressor from the vehicle motor including means for driving the compressor at a constant speed whenever the vehicle motor is running above a predetermined low speed.

17. Refrigerating apparatus comprising in combination a motor vehicle, a variable speed motor for driving the vehicle, a refrigerating system including a compressor, and means for mechanically driving the compressor from the vehicle motor including an over-running clutch for driving the compressor at a constant speed during variations in motor speed above a predetermined value.

In testimony whereof we hereto affix our signatures.
